UNITED STATES PATENT OFFICE

169,393

FLASHLIGHT

Milton M. Rockmore, New Rochelle, N. Y.

Application December 23, 1952, Serial No. 22,829

Term of patent 14 years

(Cl. D48—24)

To all whom it may concern:

Be it known that I, Milton M. Rockmore, a citizen of the United States, and a resident of New Rochelle, county of Westchester, and State of New York, have invented a new, original, and ornamental Design for a Flashlight, of which the following is a specification, reference being had to the accompanying drawings, forming part thereof.

I claim:

The ornamental design for a flashlight, substantially as shown.

MILTON M. ROCKMORE.
